DESIGN FOR A POLE-HOLDER.

56,197.

Specification for Design. Patented Aug. 24, 1920.

Application filed March 8, 1920. Serial No. 364,302. Term of patent 14 years.

To all whom it may concern:

Be it known that I, RAYMOND A. SCHULTZ, a citizen of the United States, residing at Rochester, in the county of Monroe and State of New York, have invented a new, original, and ornamental Design for a Pole-Holder, of which the following is a specification, reference being had to the accompanying drawing, forming part thereof.

The figure is a perspective view of a pole holder, showing my new design.

I claim:

The ornamental design for a pole holder as shown.

In testimony whereof I affix my signature.

RAYMOND A. SCHULTZ.
